(57) **CLAIM**

The ornamental design for an oil funnel, substantially as shown and described.

DESCRIPTION

FIG. 1 is a front perspective view of a version of the oil funnel showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is cross-sectional view taken along 8-8 of FIG. 6. The broken lines shown in the drawings represent environmental matter and form no part of the claimed design. The design is not limited to the scale shown herein.
